2,913,774

FINE SPREADER

Charles MacKinnon, Plymouth, Mass., assignor to Plymouth Cordage Company, Plymouth, Mass., a corporation of Massachusetts

Application October 31, 1955, Serial No. 543,805

4 Claims. (Cl. 19—129)

This invention comprises a new and improved fine spreader for drawing, combing and spreading hemp, jute, sisal and similar fibers in preparing them for the manufacture of cordage. The invention resides in the novel combination of a slow speed screw-operated unit with a chain or push bar unit operating at a higher speed, the units being so constructed and arranged as substantially to eliminate any intermediate zone between them.

Machines for this general purpose now available to the industry are described in prior patents, for example, U.S. No. 1,191,959, July 25, 1916, Good. They comprise a slow speed chain unit operating a series of gill bars which comb and spread the fibers, combined with a high speed chain unit operating a series of gill bars that engage the fibers advanced by the slow speed unit, drafting the fibers and at the same time subjecting them to further combing, straightening and spreading thus converting them into the form of sliver suitable for twisting.

In machines like those of the patent there is an intermediate zone in which the gill bar pins of the slow speed unit begin to withdraw and do actually withdraw from the fiber and before the pins of the high speed unit begin to engage the fiber. In that intermediate zone the fibers are not under complete control and moreover a troublesome loss occurs by the dropping out of short fibers. Ordinarily the length of this intermediate zone is approximately the distance between the axis of the sprocket chain wheels at the delivering end of the slow speed unit and the axis of the sprocket chain wheels at the receiving end of the high speed unit, a distance of 14 or 15".

I have discovered that this objectionable intermediate zone or blind spot may be substantially eliminated or at least greatly reduced in length and the loss of short fibers materially lessened by combining a slow speed unit of the screw-operated type with a high speed unit of the chain or push bar type; and by the novel construction and arrangement of these elements or units, old in themselves, is derived new and unexpected results of outstanding value to the industry.

In one aspect my invention may be defined as a screw-operated unit having a series of faller bars and means for advancing them in procession at a predetermined speed, in combination with a chain bar unit having a series of gill bars and means for advancing them at a substantially greater speed than the faller bars, the two units being closely interconnected end to end whereby fiber delivered by the faller bars is immediately received for draft by the fastener moving gill bars.

Preferably as herein shown the path of screw operated faller bars is such that their pins do not fully disengage the fiber until the pins of the chain-operated gill bars begin to take over control.

These and other features of the invention will be best understood and appreciated from the following description of a preferred embodiment thereof, selected for purposes of illustration and shown in the accompanying drawings in which:

2

Figs. 1, 2 and 3 are plan views which together show the whole machine.

Figs. 4, 5 and 6 are corresponding views in elevation.

Figs. 7 and 8 are fragmentary views showing parts of 5 the faller bars together with their lowering and lifting cams respectively,

Fig. 9 is a view in perspective of a faller bar, and

Figs. 10 and 11 are views in perspective of gill bars of the chain and push type respectively.

10 The slow speed screw-operated unit of the machine, as shown in Figs. 1 and 4 comprises an elongated frame including side bars 10 and 11 having a series of brackets 12 which support a pair of upper horizontal guides 13 and 14 and a corresponding pair of lower guides 15. 15 These are located directly below the upper guides, one being shown in Fig. 4. A series of faller bars 16 having upstanding pins 17 are arranged to travel forwardly or toward the left on the upper guides 13 and 14 and rearwardly toward the right on the lower guides 15. The 20 construction of faller bars is best shown in Fig. 9. Each bar is provided at both ends with a head having in one face a vertical slot 18 and an inclined flange 19 shaped to mesh with the operating screws.

The unit includes a pair of lead screws 20 and 21, the 25 screw 20 being fast to a horizontal shaft 22 and the screw 21 being fast to a shaft 23 journaled at their outer ends in brackets 12' secured to the side frames. The shaft 22 carries a gear 24 and the shaft 23 a similar gear 25. The unit also includes a pair of lower shafts 30 26 which are journaled in the frame immediately beneath the shafts 22 and 23. These shafts carry corresponding lower lead screws 27 mounted directly beneath the screws 20 and 21. The shaft 26 carries a pinion 28 which meshes with the gear 24 on a shaft 22 and drives 35 it in the opposite direction to that of the shaft 26. That shaft extends rearwardly and is provided with a bevel gear 29 at its rear end meshing with a corresponding bevel pinion 30 on a transverse drive shaft 31. The shaft 31 is provided at one end with a gear 32 which is part 40 of the driving train of the unit leading to any suitable source of power. The shaft disposed beneath the upper shaft 23 is likewise provided with a pinion 33 meshing with a bevel pinion 34 on the shaft 31, and by the mechanism described up to this point it will be apparent 45 that all four of the lead screws of the unit are driven simultaneously so that the faller bars 16 are advanced by the upper pair of screws along the guides 13 and 14 and retracted upon the guides 15 by the lead screws 27. The upper guides 14 and 15 are advantageously located 50 with closer spacing than the screws 20, 21 and between the latter, thus supporting the faller bars at points offset inwardly with respect to their points of driving connection with the screws.

The faller bars 16 are transferred downwardly at the 55 left hand end of the unit by cams 36 and 36' mounted respectively on the two upper lead screw shafts 22 and 23 in cooperation with the guides 41 and 41'. They are transferred upwardly at the right hand end of the unit by cams 42 and 43 on the two lower shafts 26 respectively in cooperation with the fixed upwardly and downwardly inclined guides 40. The raw material is delivered 60 by a pair of feed rolls 38, 39 to the screw-operated unit at a speed somewhat less than that of the travel of the faller bars.

65 The high speed chain-operated unit of the machine as shown in Figs. 2, 3, 5 and 6 comprises an elongated frame 50 upon the sides of which are mounted a series of upstanding brackets 51. A transverse shaft 52 provided with a pair of spaced sprocket wheels 53 and 53' 70 is journaled near the right end of the unit in bearings 54 and 54' fast to the sides of the frame. A second transverse shaft 55 provided with sprocket wheels 56

and 56' is journaled in bearings 57 and 57' near the left end of the unit as shown in Figs. 3 and 6. The shaft 55 carries at one end a gear 58 meshing with the driving gear 59 connecting with any convenient source of power. Sprocket chains 60 and 60' connect the sprocket wheels 53—56 and 53'—56', the chains moving from right to left in a straight line upper pass and being returned from left to right in a lower looped path guided by an adjustable guide 61 shown in Figs. 5 and 6 and idle pulleys 62—62' mounted on a transverse shaft 63 journaled in brackets 64 projecting downwardly from the sides of the frame 50. The sprocket chains are indicated in Figs. 2 and 3 by dot and dash lines.

The sprocket chains 60 and 60' carry between each pair of links a gill bar 65 provided with a longitudinal row of upstanding pins and a head, sometimes called a dog, at each end and having an overhanging outwardly projecting guide stud 66 and a lower block 67 with a flat guide surface formed therein. One of these gill bars is shown in Fig. 10. The milled flat slots in the dogs run on the slide bars 70 and 70' supported above the side frames 50 by the brackets 51. The slides 70 and 70' extend the full length of the unit.

It will be apparent that the gill bars 65 are positively controlled in their position by the slotted dogs running on the full length slides. Curved guides 69 cooperate with sprocket wheels 53 and 53' and with a lower track 71 in controlling the path of the gill bars at the receiving end of the high speed unit. These parts guide the dogs onto the slides.

Upon leaving the high speed gill bar unit, the now combed and drafted fibers pass between a pair of rolls 72 and 73 journaled in brackets, not shown, on the machine frame and through a converging chute 74 by which the fibers are formed into a compact sliver body. The chute leads the sliver to a pair of driven rolls 75 and 76 journaled in upstanding brackets 77. From these rolls the fiber passes downwardly at right angles and under a guide roll 78 also journaled in the brackets 77 on its way to the next machinery in the line.

Gill bars 65 directly connected to sprocket chains may be employed in the high speed unit as above described, or alternatively push bars 80 like those shown in Fig. 11 may be employed. The function of these is no different from the gill bars 65, but instead of being connected to sprocket chains, each bar 80 is provided at its ends with rollers 81 and guiding heads 82 which cooperate with guide bars to control the path and position of the push bars as they travel in an endless guided path similar to that in which the gill bars are moved. The term "gill bars" is used herein to designate both the chain bars shown in Fig. 10 and the push bars shown in Fig. 11.

An inspection of Fig. 5 indicates the great advantage secured by the novel combination of slow speed screw-operated unit with high speed gill bar unit in that the pins of the gill bars 65 or 80 will be seen to move up into fibre-engaging position in substantially the same location in which the pins 17 of the descending faller bars 16 begin to withdraw from the fibres. The result is that there is substantially no loss of control of the fibre at any point in the combing and spreading process and substantially no loss of short fibre in the transition zone.

The delivery ends of the guides 13 and 14 are separated longitudinally from the sprockets 53, 53' by a space no wider than sufficient to permit a faller bar 16 to pass downwardly to the lower lead screws 27. It is in this space that the pins of the gill bars 65 pass upwardly and so take control of the fibre as it is being relinquished by the pins of the faller bars 16.

Having thus disclosed my invention and described in detail an illustrative embodiment thereof, I claim as new and desire to secure by Letters Patent:

- 4
1. A fine spreader comprising a screw-operated unit and a chain-operated unit constructed and arranged to act consecutively and without an interposed intermediate zone upon advancing fibre, the screw-operated unit having a series of faller bars, a pair of parallel horizontal screws for advancing the bars in procession at a fixed speed, and the chain-operated unit having a series of gill bars, chains for advancing the gill bars at a greater speed than the faller bars, and sprocket wheels for driving the chains offset inwardly with respect to the delivery ends of said screws and spaced longitudinally relative to said delivery ends by approximately the width of a faller bar, whereby fibre delivered by the faller bars is immediately received for draft by the gill bars.
  - 15 2. A fine spreader comprising a screw-operated unit and a chain-operated unit constructed and arranged to act consecutively and without interruption upon advancing fibre, the screw-operated unit having a pair of horizontal guides at a fixed height, a series of faller bars movable thereon and screws connected to the faller bars at points spaced laterally beyond the guides, and the chain-operated unit having a pair of guides mounted at substantially the same fixed height, offset laterally with respect to the guides of the chain-operated unit and spaced longitudinally relative to said delivery ends by approximately the width of a faller bar, a series of gill bars and chains for advancing the gill bars on said latter guides.
  - 20 3. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
  - 25 4. A fine spreader comprising a slow speed unit and a high speed unit constructed and arranged to act consecutively and without interruption upon advancing fibre, the slow speed unit having a pair of parallel rotary screws, guides spaced inwardly with respect to the screws, a series of faller bars meshing at their ends with the screws and advanced thereby at a fixed rate of travel along said guides, the high speed unit having tracks disposed in end to end relation to said screws, offset outwardly with respect to the guides and spaced longitudinally from said rotary screws not substantially more than the width of a faller bar, a series of gill bars movable along the tracks, and means for advancing the gill bars at a faster rate of travel than the faller bars whereby the fibre is continuously engaged by the pins of the faller bars or the pins of the gill bars as passing from one unit to another.
  - 30 5. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
  - 35 6. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
  - 40 7. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
  - 45 8. A fine spreader comprising a slow speed unit and a high speed unit constructed and arranged to act consecutively and without interruption upon advancing fibre, the slow speed unit having a pair of parallel rotary screws, guides spaced inwardly with respect to the screws, a series of faller bars meshing at their ends with the screws and advanced thereby at a fixed rate of travel along said guides, the high speed unit having tracks disposed in end to end relation to said screws, offset outwardly with respect to the guides and spaced longitudinally from said rotary screws not substantially more than the width of a faller bar, a series of gill bars movable along the tracks, and means for advancing the gill bars at a faster rate of travel than the faller bars whereby the fibre is continuously engaged by the pins of the faller bars or the pins of the gill bars as passing from one unit to another.
  - 50 9. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
  - 55 10. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
  - 60 11. A fine spreader comprising a screw-operated unit and a chain-operated unit constructed and arranged to act consecutively and without an interposed intermediate zone upon advancing fibre, the screw-operated unit including a pair of parallel spaced horizontal screws and a series of faller bars having upstanding pins and being meshed at their opposite ends with their screws, a chain-operated unit including a pair of sprocket wheels mounted on a transverse shaft, longitudinally spaced from the delivery ends of the screws by no more than approximately the width of a faller bar and offset inwardly with respect to said screws; sprocket chains running on said wheels, and a series of gill bars carried by the chains and moved thereby to engage and control fibre simultaneously with its disengagement by the pins of the faller bars.
